TYPEWRITING MACHINE

William A. Dobson, Wethersfield, Conn., assignor
to Underwood Elliott Fisher Company, New
York, N. Y., a corporation of Delaware

Application December 10, 1936, Serial No. 115,095

4 Claims. (Cl. 197—81)

This invention relates to stop-devices employed in typewriter case-shift mechanisms.

Certain stop-devices heretofore used include noise-reducing cushioning means such as leather, felt, rubber, cork, or the like, which, being yielding and soft, do not stand up or wear well and therefore these devices are not effective to maintain the requisite accuracy of movement to which the case-shift parts must be limited by the stop-devices.

The conventional solid metal abutments heretofore used are too noisy.

A feature of my invention is the provision of an inexpensive stop-abutment capable of arresting a case-shift mechanism with accuracy, and so quietly as to be comparable with the old cushioned abutments.

I obtain the result by constructing an abutment of a wide flexible button formed of steel or other hard material possessing only slight yieldability. The steel button, after being formed, is left soft. A central concavity may be formed in the top, so that the rim may yield slightly under impact, to absorb the noise-producing vibration. The rim is not so yieldable but that a precise and accurate arresting stop is provided and, when the device is applied to a typewriter case-shift, accurate aligning of the platen is procured.

The arresting button may be centrally mounted on top of an adjusting screw which may also support a locking nut, so that the arresting position of the stop may be varied and set. A good quality steel assures both a good decibel standard and permanence of precision.

The bottom of the concave recess may provide a positive stop against excessive bending of the rim of the arresting device. The recess should be preferably shallow and broad so that the center and bottom of the cavity, which is positioned directly over the mounting and adjusting screw, when intercepted by the moving or striking part, provides a positive check against excessive yielding of the rim downward.

Another feature of the invention is the provision of a novel device for locking the case-shifting mechanism in lower-case position, to prevent platen rebound and thereby to assure a perfect alignment of the line of typing. The end of the shift-key lever may be provided with a depending tooth which overlies the upper rear edge of an upwardly extending finger which is fixed on one of the case-shift lift arms; the tooth is raised to clear the finger before the shift-key lever raises the lift arm and the lift arm moves the finger into locking position before the return

spring on the shift-key lever lowers the depending tooth into locking position. The bottom of the tooth may be rounded to facilitate the movement into locking position. The locking tooth may be mounted for forward and backward adjustment on the end of the shift-key lever.

Other features and advantages will hereinafter appear.

In the accompanying drawing:

Figure 1 is a top-front view at an angle of 45°, 10 with a part of the silencer stop broken out.

Figure 2 is a side elevation of the inside of the frame showing two opposed stops and the case-shift lift arm in upper-case typing position.

Figure 3 is a side elevation showing an adjustable lock for locking the case-shift in lower-case position.

Figure 4 is a side elevation partly sectioned to show the contacting relationship of the extension on the case-shift lift arm and the silencing 20 stop.

Figure 5 is a view similar to Figure 4 but showing an exaggerated and magnified bending of the silencing stop.

Figure 6 is a view similar to Figure 4 but showing a further exaggerated and magnified bending of the silencing stop to the final limit in which the engagement of the extension on the case-shift lift arm and the bottom of the top cavity on the silencing stop takes place.

A typewriter frame 10 is mounted on the usual legs 11. A shift-key lever 12 is pivoted on a cross-rod 13 mounted in the frame 10. A stop-pin 14 in the side of the frame 10 determines the initial position of the shift-key lever and a coil spring 35 15 is fastened to the shift-key lever on the opposite side of the pivot-rod 13 and to the frame 10 and thereby tends to return the shift-key lever 12 to the initial upper position.

A downwardly and rearwardly inclined arm 16 40 has a top level operating edge 17, the latter engaging a transverse pin 18 mounted on a case-shift lift arm 19 which is mounted on a rock-shaft 20 for reciprocation therewith, the shaft being journaled in the sides of the frame 10. The pin 45 18 engages an aperture in the shift-frame 22 to actuate the latter in case-shift movement. Also mounted on the rock-shaft 20 is an upstanding finger 21. In the normal idle position of the shift-key lever 12 and the lower-case position of the 50 case-shift lift lever 19 the pin 18 lies a bit above the operating edge 17, thereby permitting upward motion of the rear of the shift-key lever before the edge 17 engages and actuates the pin 18 to raise the lift arm 19 and the shift-frame 22 55

which is mounted to slide upwards and downwards in the frame 10 by a pin-and-slot connection 23, as is well known in the art. The shift-frame 22 supports tracks 24, 25 which together with tracks 26, 27, mounted on the platen-carriage 29, engage anti-friction balls 28. A rotatably mounted platen 30 is engageable by a type-bar 31 in a manner well-known in the art. The depression of the shift-key elevates the platen to the upper-case type position 32.

The case-shift lift arm 19 has an extension 33 which projects forwardly in substantially a horizontal direction to lie between parallel horizontal ears 34, 35 mounted on the inside of the side wall of frame 10 and projecting inwardly. The ears 34, 35 have holes centered on a perpendicular line which are internally threaded to receive identical screws or studs 36, each of which has in its end a slot 37 to secure a screw-driver. The screw 36 is not threaded near the top, to leave a section 38 which acts as a stop and spacer for a nut 39, the latter forming a massive body portion on the stud 36 and having the usual hexagonal periphery to receive an adjusting wrench. Lock nuts 40 engage the ears 34 to lock the screws 36 in any adjusted position.

Each screw 36 supports on its top a relatively thin arresting stop or diaphragm 41 centrally positioned thereon. This stop 41 may be spaced from the top of nut 39 by the length of the section 38 and may have a flat bottom 45 and on the top is dished to form a circular shallow centrally positioned concavity 46 which forms a flat-topped rim 47, the periphery of which may be of identical polygonal form with that of the body portion 39. The cavity 46 is preferably broad and shallow, in fact sufficiently shallow to permit the rim 47 to flex downwardly on opposite sides at the same time as shown exaggerated in Figure 6 so that the bottom 48 of the concavity forms a positive final stop for the lower straight edge 49 of extension 33 in the case of the lower stop 41, and for the angularly disposed upper straight edge 50 of the extension 33, in the case of the upper stop 41. This prevents fatiguing and prevents breakdown of the diaphragm 41. The steel of the arresting stop-button 41 is preferably left soft to give the desired flexibility and silencing property, and when the silencer stop 41 is tested on a decibel machine, the result compares favorably with cushioning stops that are utterly lacking in the accuracy of alignment of the platen and the actuating longevity inherent in the present invention. The body portion 39 may also serve to choke some of the noise-producing vibrations set up in the screw 36.

The shift-key lever 12 terminates in a rearward arm 52 having near the rear end a central elongated slot 53. A piece 54 carries at the outer end a depending tooth 55, the front edge of which is adapted to engage the upper rear straight edge

of the finger 21. The piece 54 has bent-over tabs 56 which slidably engage opposite edges of the arm 52. A set screw 57 passes through the slot 53 and is centrally secured on the piece 54, the overlying head of the screw pressing on the near side of the arm 52, as shown in Figure 3.

The play between the inclined edge 17 of the arm 16 and the pin 18 permits the tooth 55 to rise high enough to clear the top of the finger 21 when the shift-key is depressed, and also permits the finger 21 to fall into the initial position. The tooth 55 may be appropriately curved at the bottom to permit sliding engagement into the engaging position over the top of the finger 21.

Variations may be resorted to within the scope of the invention, and portions of the improvements may be used without others.

Having thus described my invention, I claim:

1. In a case-shift mechanism for typewriters, a silencing stop engageable by a member of the mechanism for limiting relative movement of the platen to the type, and comprising, a mounting stud, and a flexible metallic diaphragm carried on the end of said stud and adapted to flex laterally upon engagement with said member.

2. In a case-shift mechanism for typewriters, a silencing stop engageable by a member of the mechanism for limiting relative movement of the platen to the type, and comprising, a mounting stud, and a flexible metallic diaphragm carried on the end of said stud and presenting a substantially broad area to the path of said member, a medial portion of the area being concave to present a limited marginal area for engagement with said member.

3. In a case-shift mechanism for typewriters, a silencing stop engageable by a member of the mechanism for limiting relative movement of the platen to the type, and comprising, a slim mounting stud, a flexible, thin metallic button carried on the end of said stem, presenting a substantially broad area to said member and adapted to flex laterally upon engagement with said member, and a massive body portion on said stem adjacent but spaced from said button to dampen impact vibrations imparted to said stop.

4. In a case-shift mechanism for typewriters, a silencing stop engageable by a member of the mechanism for limiting relative movement of the platen to the type, and comprising, a mounting stud, and a flexible, thin metallic diaphragm having a shallow concavity in the face thereof confronting said member and presenting a marginal area only for initial engagement by said member, said diaphragm being adapted to flex upon engagement by said member to the extent of the depth of the concavity, the extent of flexure being limited by said member engaging the bottom of the concavity.
